CLAIM

The ornamental design for a telescoping computer mount, as shown and described.

DESCRIPTION

FIG. 1 is a rear perspective view of a telescoping computer mount showing our new design;

FIG. 2 is a top plan view thereof;

FIG. 3 is a rear elevational view thereof;

FIG. 4 is a bottom plan view thereof;

FIG. 5 is a right side elevational view thereof;

FIG. 6 is a front side elevational view thereof; and,

FIG. 7 is a left side elevational view thereof.

The broken line drawing of a computer in all views is for illustrative purposes only and forms no part of the claimed design.
